GEORGE SCHRODER

BY *J. M. Wright*,

ATTY.

UNITED STATES PATENT OFFICE.

GEORGE SCHRODER, OF BERKELEY, CALIFORNIA.

NEEDLE-PLATE FOR SEWING-MACHINES.

1,232,723.

Specification of Letters Patent. Patented July 10, 1917.

Application filed April 10, 1917. Serial No. 160,987.

To all whom it may concern:

Be it known that I, GEORGE SCHRODER, a citizen of the United States, residing at Berkeley, in the county of Alameda and State of California, have invented new and useful Improvements in Needle-Plates for Sewing-Machines, of which the following is a specification.

The present invention relates to improvements in needle plates on machines for stitching soles of shoes having a straight needle and awl.

On needle plates for stitching leather soles to uppers, it is necessary to form a cutter for cutting a groove in the leather sole. Recently rubber soles have come greatly into use, and in such soles a groove should never be cut as in leather soles. Consequently, it has been the practice to provide two needle plates, one with a cutter for cutting the grooves in leather soles, and the other without the cutter, for rubber soles.

It takes a good deal of time and unpleasant labor to remove the screws in a confined space on a hot needle plate cap in order to change from one of these plates to another.

It is the object of the present invention to provide a needle plate which can be used for stitching either a rubber or a leather sole and in which the labor and time required for adjustment is very small.

In the accompanying drawing, Figure 1 is a front view of a cap having thereon a needle plate constructed in accordance with my invention; Fig. 2 is a plan view of the needle plate removed; Figs. 3 and 4 are sectional views on the lines 3-3 and 4-4 respectively of Fig. 2.

Referring to the drawing, 1 indicates a needle plate cap of the present construction and 2 indicates my improved needle plate. Said needle plate is formed with a centrally located countersunk hole 3 by which it may be secured by a screw 4 to the needle plate cap, and on which as a pivot the needle plate can be turned. Said needle plate is formed with two extensions 5 and 6 from said hole 3 in directions at right angles to one another. In the extension 5 is formed a tangentially directed slot 7 for the sewing machine needle, said slot being used when said needle is used for stitching rubber soles. In the other extension 6 is a tangentially directed slot 8, and in line with said slot at one end thereof is a cutter 9, said slot 8 being adapted to receive the sewing machine

needle when stitching leather soles, and the cutter 9 being for the purpose of cutting grooves in said soles. The outer edge 11 of the extension 6 is beveled, as shown in Fig. 4, while the outer edge of the extension 5 is of uniform thickness, as shown in Fig. 3. For the purpose of quickly adjusting the needle plate from its position suitable for stitching leather soles to its position suitable for stitching rubber soles, or conversely, I have formed in the needle plate an arcuate slot 12 to receive the shank of a screw 13, the plate at each end of the slot 12 having a countersunk portion 14 sufficiently large to receive the head of the screw. Said screw 13 is, in either position of the needle plate, screwed into a hole in the needle plate cap. The method of moving the needle plate from one position to another is very easy and rapid. To do this, first, the screw 13 is unscrewed sufficiently to bring its head out of the countersunk portion 14 provided therefor. Then, the screw 4 being sufficiently loose, or loosened, to permit the plate to be turned, said plate is turned through a right angle, the central portion of the arcuate slot moving past the shank of the screw 13 and the plate 2 at the margins of said slot moving under the head of the screw 13, until the said head is immediately over the countersunk portion of the plate at the other end of said slot. The screw 13 is then screwed down so that its head is received in said countersunk portion. If desired, the screw 4 can also be screwed down tight to the needle plate.

I claim:

1. A needle plate provided with a hole through which can be passed a pivoted screw to be screwed into a needle plate cap and upon which said plate can be turned, said plate having, in portions extending from said pivoted screw at right angles to each other, slots extending at right angles to each other, and also having, in line with one of said slots and at one end thereof, a cutter for cutting leather, said plate having also, in a part on the other side of said hole from said slots, a slot extending in a circular arc of 90° about the pivot hole as center, and means for clamping said plate to the needle plate cap at either end of said arcuate slot.

2. A needle plate provided with means for pivoting it to a needle plate cap, and having two slots each extending in a tangential direction with reference to said pivotal

means, having also a cutter at one end of said slots and in line therewith, having also a slot extending in an arc of a circle about the pivotal means as center and subtending at said pivotal means an angle equal to the angular distance between the centers of said two slots, and means adapted to extend through either end of said last-named slot for clamping said needle plate to the needle plate cap.

3. A needle plate provided with means for pivoting it to a needle plate cap, and having two slots each extending in a tangential direction with reference to said piv-

otal means, having also a cutter at one end 15 of said slots and in line therewith, having also a slot extending in an arc of a circle about the pivotal means as center and subtending at said pivotal means an angle equal to the angular distance between the centers 20 of said two slots, each end of said last-named slot being countersunk to receive the head of a screw which can be screwed into the hole in the needle plate cap, said slot being sufficiently wide to receive the shank screw 25 but not the head.

GEO. SCHRODER.
